UNITED STATES PATENT OFFICE.

FRANCIS J. HANRAHAN, OF RUPERT, PENNSYLVANIA.

LEVER MECHANISM.

1,031,440.

Specification of Letters Patent.

Patented July 2, 1912.

Application filed June 5, 1909. Serial No. 500,319.

To all whom it may concern:

Be it known that I, FRANCIS J. HANRAHAN, a citizen of the United States, residing at Rupert, in the county of Columbia and State of Pennsylvania, have invented a new and useful Lever Mechanism, of which the following is a specification.

This invention has reference to improvements in lever mechanisms for engines and is designed more particularly to increase the power transmitted from the reciprocating piston rod of the engine to the crank shaft. For this purpose there is provided a lever system by means of which the piston stroke may be increased and the expansive force of the steam utilized for a longer relative period than usual.

The invention will be best understood from a consideration of the following detail description taken in connection with the accompanying drawings forming a part of this specification, in which drawings,

Figure 1 is a side elevation of the improved engine in one phase of its operation. Fig. 2 is a similar view of the engine in another phase of its operation. Fig. 3 is a perspective view of one of the levers used in the connecting mechanism. Fig. 4 is a slide used in connection with the structure of Fig. 3.

Referring to the drawings there is shown a frame 1 constituting the frame of the engine and this frame may be mounted upon a bed 2 of any suitable construction. Near one end of the frame there is journaled a shaft 3 carrying at one end a fly-wheel 4 and at the other end a crank disk 5, although of course the crank disk may be replaced by an ordinary crank. In the particular structure shown the shaft 3 carries at an intermediate point a pulley 6 but this arrangement of the parts may be varied at will. Near the other end of the frame 1 there is mounted a cylinder 7 with its usual steam chest 8 in which latter may be located the usual slide valve receiving motion from a pitman 9 connected to a shaft 10 which is actuated by an eccentric 12, all these parts being of the usual construction.

The piston rod of the engine, indicated at 13, is connected to the usual cross-head 14 capable of sliding in guideways 15.

Erected on the frame 1 between the shaft 3 and the outer end of the guideways 15 is a standard 16 to which is pivotally connected a lever 17, the pivot connection 18 of which

is near the top of the standard and the lever is disposed pendants with its lower end removed from the pivot 18 connected by a link 19 to the cross-head 14.

Mounted on the standard 16 at a point below the pivot 18 and in the same vertical plane is a lever 20 free to turn on a pivot stud 21 projecting from the standard 16. This lever 20 is provided at the upper end with a longitudinal slot 22 in which there is mounted a block 23 capable of sliding longitudinally in the slot and this block has a pin 24 projecting therefrom through the lever 17 at an appropriate point thereon. The other or shorter end of the lever 20 is connected by a pitman 25 to a crank pin 26 on the crank disk 5.

Let it be assumed that the fly-wheel 4 is rotating clockwise as viewed in Figs. 1 and 2 then the crank pin 26 may be assumed to be moving off dead center while the piston of the engine is at the rear of cylinder 7. As the piston moves forward the lever 17 is swung from the position shown in Fig. 1 toward the position shown in Fig. 2, moving forwardly through an arc described about the axis of the stud 18. The lever 17 is a lever of the second class and is connected at an intermediate point by means of the slide 23 to one end of the lever 20 which is the lever of the first class and the longer end of the lever 20 will move through the arc described by the connection between the two levers. This is more distant from the pivot point 21 than is the point of connection of the pitman 25 with the other end of the lever 20.

Considering the resistance to the rotation of the shaft 3 as the load then less power may be applied to the lever 20 at the stud 24 to cause the rotation of the shaft than would be the case if the power were applied directly to the crank stud 26.

Since the connection between the levers 17 and 20 is intermediate between the pivot stud 18 of the lever 17 and the connection of the crank 19 with said lever 17, the power necessary to move the lever 17 against the force resisting such movement is less than the said force. Consequently the power applied at the outer end of the lever 17 is materially less than the force applied at the crank pin or stud 26 to rotate the shaft 3.

Because of the increased movement of the outer end of the lever 17 over and above the movement of the crank pin or stud 26,

the cylinder 7 may be made longer than though the cross-head 14 were directly connected to the crank pin 26 and the expansive force of the steam within the cylinder may 5 be exerted for a correspondingly longer period, thus permitting not only a lower steam pressure for the initial steam pressure, but a longer stroke of the piston is available for the same movement of the crank pin upon 10 the shaft 3.

What is claimed is:—

1. In a motor, a guideway, a member mounted for reciprocation therein, a standard fixed relative to the guideway, a crank, 15 said standard being interposed between the crank and the guideway, a lever pivoted at one end to the standard, a pitman connected to the reciprocating member and pivoted to the other end of the lever, both pivots being relatively fixed, a slide pivotally mounted upon the lever at a point between the ends thereof, the pivot for the slide being fixed with relation to the first mentioned pivots, 20 a lever fulcrumed upon the standard at a point between its ends and formed with a slot in which the slide reciprocates, the slot being located at one end of the last mentioned lever; and a pitman having fixed piv- 25

otal connection with the last mentioned lever at its other end and connected to the 30 crank.

2. In a motor, a crank, a guide, a cross-head mounted for reciprocation in said guide, a standard disposed intermediate of and above said guide and crank, a lever having its upper end pivoted near the upper end to the standard and having its lower end free and operably connected to the cross-head, a lever shorter than the first lever and pivoted intermediate of its ends to the standard below and in line with the pivotal point on the first lever, a co-acting and sliding pivotal connection between the upper end of the second lever and the first lever, said connection being intermediate of the ends of the 45 first lever, and a pitman pivotally connected to the lower end of the second lever and the crank.

In testimony that I claim the foregoing as my own, I have hereto affixed my signature in the presence of two witnesses. 50

FRANCIS J. HANRAHAN.
